UNITED STATES PATENT OFFICE

ALVARADO L. R. ELLIS, OF SWAMPSCOTT, MASSACHUSETTS, ASSIGNOR TO GENERAL ELECTRIC COMPANY, A CORPORATION OF NEW YORK

PIEZOELECTRIC OSCILLATOR

Application filed May 11, 1926. Serial No. 108,367.

My invention relates to oscillators comprising a piezo-electric element such as a crystal of quartz, or the like, and has for its principal object the provision of an improved mounting which is so constructed as to permit ready assembly and accurate adjustment of the oscillator parts. Further objects are the provision of a mounting which permits the electrodes of the oscillator to be readily locked together when the spacing between them has been adjusted and which obviates or greatly minimizes the effect of temperature changes on the operating characteristics of the oscillator.

It is well known that a piezo-electric element, such as a crystal of quartz or the like, will oscillate at a frequency dependent on its dimensions when subjected to an electrostatic field and that this characteristic of the piezo-electric element may be utilized to predetermine very accurately the frequency at which current is supplied from a source to an output circuit. In order to ensure the best operation of the piezo-electric oscillator, it is desirable that the surfaces of the electrodes and the active surfaces of the piezo-electric element be maintained substantially parallel, that the electrode surfaces be accurately spaced from one another, and that means be provided for preventing change in this spacing when it is once adjusted. If a piezo-electric element is inserted between fixed electrodes connected in a suitable circuit, it is probable that this element will oscillate and control the circuit but there is a possibility that it will not oscillate at all and a probability that it will not oscillate with anything like its maximum effect. The activity of the crystal is a very important matter for the reason that it determines the number of stages required between the input and output circuits. In order to insure the proper operation of the piezo-electric element, it is essential that the element be properly mounted between the electrodes.

What takes place in a piezo-electric cell will be readily understood by considering the mechanical coupling of the electrodes and piezo-electric element as the air gap between the element and the electrodes is increased.

Starting with the electrodes in contact with the surfaces of the element or crystal, the frequency of the crystal decreases to a certain minimum and then increases as the air gap is increased to approximately one tenth the thickness of the crystal when the crystal stops oscillating. The actual length of the air gap at which oscillation of the crystal ceases is dependent upon the ratio of the velocity of sound in quartz and in air. This ratio varies with the temperature and slightly with different crystals. It also depends somewhat on the way in which the element is cut from the crystal.

The activity of the oscillator slab through the same range of adjustment of the air gaps starts off rather feebly when in contact, and increases rapidly reaching a maximum when the air gap is approximately one fifteenth the thickness of the oscillator slab. With a further increase in the air gap, the activity of the crystal rapidly decreases and ceases to oscillate when it becomes approximately one tenth the thickness of the oscillator slab. Unless the oscillator slab is an exceptionally active one, it usually ceases to oscillate before the air gap has been increased to one tenth.

The reason for this behavior is due to combination of the effect of air loading upon the apparent thickness of the oscillator slab due to the air being forced in and out between the electrodes, and the effect of mechanical coupling between the oscillator slab and the electrodes due to the time phase relation of the reflected compression wave in the air gap and that in the oscillator slab. When the electrodes are nearly in contact with the oscillator slab, the reflected compression wave in the air gap is nearly 180 degrees out of phase with the compression wave in the oscillator slab and is assisting. When the air gap is approximately one fifteenth the thickness of the oscillator slab the compression wave is in phase and the amplitude of the oscillator slab is a maximum, consequently its output is a maximum. As the air gap is further increased the reflected compression wave in the air gap becomes more and more out of phase until when one tenth the thickness of the oscilla-

tor slab it is 180 degrees out of phase, and in direct opposition, and therefore reduces amplitude of the oscillator slab to the point where it prevents any but the most extraordinary crystals from oscillating. In accordance with my invention, proper operation of the element is produced by means of a construction wherein the spacing between the electrodes is readily adjusted and wherein the electrodes are securely fixed or mechanically locked together with any desired spacing between them.

My invention will be better understood from the following description when considered in connection with the accompanying drawings, and its scope will be pointed out in the appended claims.

Referring to the drawings, Figs. 1 to 4 shows various views of a piezo-electric oscillator constructed in accordance with my invention; and Fig. 5 shows a modified arrangement for locking the electrodes together when the spacing between them has been adjusted.

Figs. 1 to 4 show electrodes 1 and 2 which are mounted on an insulation base 3, are connected to the plug terminals 4 and 5 respectively and are surrounded by an insulation cover 6 which is removably attached to the insulation base 3 and is provided for protecting the electrodes against temperature changes. It should be noted that the electrode 2 is attached to the insulation base 3 by means of screws 7, that the adjustable electrode 1 is threaded into a support member 8 which is attached to the insulation base 3 by means of screws 9, that the insulation cover 6 is attached to the base 3 by means of screws 10, and that a cylinder 11 of some resilient material such as celluloid, hard rubber, or bakelite, is mounted within the support or wall member 8 to act as a shock absorber for the piezo-electric element, which is normally supported between the electrodes 1 and 2.

The manner in which the electrode 1 is locked in any position to which it has been adjusted will be readily understood upon consideration of Figs. 3 and 4. As indicated by these figures, the wall or support member 8 is threaded on its inner periphery to fit the edge of the electrode 1 loosely and is thereafter deformed at points 12, 13 and 14 so that the adjustable electrode 1 will not quite thread into it. In order to permit adjustment of the electrode 1 along the threaded part of wall member 8, an adjustment ring 15 is provided. This ring is provided with projections 17 and 18 at its inner periphery and with a thumb-screw 19 which is spaced from these projections and extends through the inner periphery of the ring.

When it is desired to adjust the electrode 1, the adjustment ring 15 is so positioned

around the deformed wall member 8 that the points of greatest deformation toward the center of the ring are between the projections 17 and 18. The thumb-screw 19 is then tightened against the outer wall of the member 8, thus restoring this member to a substantially circular form and permitting ready adjustment of the electrode 1. Upon removal of the adjustment ring the wall member 12 tightly binds the electrode 1 at the points 12, 13 and 14, thereby securely locking it in the position to which it has been adjusted.

Fig. 5 shows an adjustable electrode 1 provided with a flange 20 through which jamb screws 21 are threaded for the purpose of locking the electrode in any position to which it is adjusted.

It will be apparent that the locking arrangement shown by Figs. 3 and 4 differs from that shown by Fig. 5 in that there is no visible means of adjustment when the adjustment ring has been removed. This feature is of advantage in that it makes it impossible for anyone who is unfamiliar with the construction to tamper with the adjustment. The insulation casing 6 not only protects the oscillator from dirt and moisture, but also prevents change in the spacing between the electrodes due to sudden changes in temperature.

The form of the invention shown by Figs. 1 to 4 of this application is specifically claimed in an application of Alexander J. R. Fiego, Serial No. 102,342, filed April 15, 1926, and assigned to the same assignee as the present application.

The embodiments of the invention illustrated and described herein have been selected for the purpose of clearly setting forth the principles involved. It will be apparent, however, that the invention is susceptible of being modified to meet the different conditions encountered in its use, and I therefore aim to cover by the appended claims all modifications within the true spirit and scope of my invention.

What I claim as new and desire to secure by Letters Patent of the United States is:—

1. A piezo-electric oscillator comprising a pair of electrodes electrically insulated from one another, and a threaded connection operable to adjust the electrode spacing and means for locking said electrodes together with any desired spacing therebetween.

2. A piezo-electric oscillator comprising a pair of electrodes electrically insulated from one another, a threaded connection operable to adjust the electrode spacing means for locking said electrodes together with any desired spacing therebetween, and a casing surrounding said electrodes and connection.

3. A piezo-electric oscillator comprising a pair of electrodes electrically insulated from one another, a mechanical connection opera-

ble to adjust the electrode spacing means for locking said electrodes together with any desired spacing therebetween, a casing surrounding said electrodes and connection, and 5 terminals extending through one side of said casing for connecting said electrodes to an external circuit.

4. A piezo-electric device comprising a pair of electrodes electrically insulated and 10 mechanically spaced from one another, a support attached to one of said electrodes, a threaded connection between said support and the other of said electrodes for adjusting the spacing between said electrodes, and 15 means for locking said connection to prevent change in the adjustment of the electrode spacing.

5. A piezo-electric device comprising a pair of electrodes electrically insulated and 20 mechanically spaced from one another, a support attached to one of said electrodes, a threaded connection between said support and the second electrode for adjusting the spacing between said electrodes, and a screw 25 threaded through the edge of the second electrode for locking said connection to prevent change in the adjustment of the electrode spacing.

6. A piezo-electric oscillator comprising a 30 pair of electrodes electrically insulated from one another, a mechanical connection operable to adjust the electrode spacing, means for locking said electrodes together with any desired spacing therebetween, and a resilient 35 collar adjacent the inner periphery of said connection.

In witness whereof, I have hereunto set my hand this 7th day of May, 1926.

ALVARADO L. R. ELLIS.
